UNITED STATES PATENT OFFICE

173,031

EXPANSIBLE LINK CHAIN FOR A WRIST BAND OR SIMILAR ARTICLE

Richard Jaccarino, Greenwich, Conn.

Application December 10, 1953, Serial No. 27,999

Term of patent 14 years

(Cl. D45—4)

To all whom it may concern:

Be it known that I, Richard Jaccarino, a citizen of the United States, residing at Greenwich, in Fairfield County, State of Connecticut, have invented a new, original, and ornamental Design for an Expansible Link Chain for a Wrist Band or Similar Article, of which the following is a specification, reference being had to the accompanying drawing, forming part thereof.

I claim:

The ornamental design for an expansible link chain for a wrist band or similar articles as shown and described.
